UNITED STATES PATENT OFFICE

PARKER Z. BLOSER, OF COLUMBUS, OHIO

DESIGN FOR A FOUNTAIN PEN

Application filed August 5, 1930. Serial No. 36,563. Term of patent 14 years.

To all whom it may concern:

Be it known that I, PARKER Z. BLOSER, a citizen of the United States, residing at Columbus, in the county of Franklin and State of Ohio, have invented a new, original, and ornamental Design for Fountain Pens, of which the following is a specification, reference being had to the accompanying drawing, forming a part thereof.

I claim:

The ornamental design for a fountain pen, as shown.

PARKER Z. BLOSER.
